Attorney.

UNITED STATES PATENT OFFICE.

HOMER F. LIVERMORE, OF BOSTON, MASSACHUSETTS.

HARNESS STUD.

Application filed March 14, 1924. Serial No. 699,367.

To all whom it may concern:

Be it known that I, HOMER F. LIVERMORE, a citizen of the United States, and a resident of Boston, in the county of Suffolk and

Commonwealth of Massachusetts, have invented certain new and useful Improvements in Harness Studs, of which the following is a full, clear, and exact specification.

10 It has heretofore been the custom in looms for the heddle bars to be supported from the harness frames by means of studs screwed up into the latter. This arrangement proves in many ways to be highly objectionable, not only by the studs working loose where they are screwed in, and necessitating plugging the screw holes to get a firm hold again, but by the getting out of alinement of the lower ends of the studs

15 and a consequent wearing and grooving of adjacent harness frames.

The object of this invention is the construction of a harness stud which cannot work loose, will not cut and groove adjacent harness frames, and which will at the

20 same time securely retain the heddle bars in place therein.

In the drawings forming part of this specification, Fig. 1 is a perspective view of 30 a portion of a harness frame and heddle bar showing the latter supported by a harness stud embodying my invention. Fig. 2 is a detail view, partly in section, of the harness stud. Fig. 3 is a perspective view of the 35 lower part thereof. Fig. 4 is an elevation from behind of the lower part of the same.

The harness frame 1 is constructed of wood, but the heddle bar 2 is of metal and suspended from the former. My improved 40 means for this suspension consists of a length of spring metal, preferably steel, bent to form a flattened loop 3 fitted to snugly

receive the harness frame 1. This loop is not complete, but is partially open at its lower end, a terminal lip 4 serving to clasp 45 beneath the under edge of the frame 1.

The other end of the spring metal 5 is bent into a hook 6 which is disposed in central alinement beneath the loop 3, as shown in Fig. 2, and which is adapted for receiving 50 the heddle bar 2. To ensure the retention of the heddle bar in the hook, a tongue 7 is struck out from the metal close above the level of the tip of the hook 6. When the bar 2 is pressed down into the hook, the 55 tongue fits in above the top edge of the bar and prevents its accidental dislodgement.

As is evident from inspection of Fig. 2, it is impossible for the tip of the hook 6 to contact with the surface of an adjacent 60 harness frame, and consequently there can be no wear and grooving from this cause. It is equally evident that the grip of the loop 3 upon the harness frame is incapable 65 of working loose, while at the same time it can be easily removed therefrom by simply springing the lip 4 away from the frame far enough to permit the loop to be drawn up and off from the frame.

What I claim as my invention is:

A harness stud comprising a length of sheet spring metal having one terminal portion bent to fit a harness frame, and its other terminal portion bent to form a hook to receive the heddle bar, the intermediate 75 section of the metal having a tongue struck out therefrom toward and spaced above the tip of said hook, whereby to keep the heddle bar securely in said hook.

In testimony that I claim the foregoing 80 invention, I have hereunto set my hand this 12th day of March, 1924.

HOMER F. LIVERMORE.
